LEO POTTER, OF NEW YORK, N. Y., ASSIGNOR TO EMIL POTTER, OF NEW YORK, N. Y.

CIGARETTE-CASE.

1,133,745.

Specification of Letters Patent. Patented Mar. 30, 1915.

Application filed May 23, 1914. Serial No. 840,428.

To all whom it may concern:

Be it known that I, LEO POTTER, a citizen of the United States, and resident of the borough of Manhattan, city, county, and State of New York, have invented certain new and useful Improvements in Cigarette-Cases, of which the following is a specification.

My invention relates to cigarette cases, and particularly to such cases which have a central holder containing the cigarettes, and its purpose is to provide a device of simple construction, which can be manufactured at a relatively low cost, and whose parts can be assembled very easily.

Reference is to be had to the accompanying drawings, in which—

Figure 1 is a vertical section of the cigarette case in the open position, taken on line 1—1 of Fig. 2; Fig. 2 is a vertical section on line 2—2 of Fig. 1; Fig. 3 is a horizontal section on line 3—3 of Fig. 1; Figs. 4 and 5 are partial cross sections taken on lines 1—1 and 5—5 respectively of Fig. 2, both views being on an enlarged scale; and Fig. 6 is a view similar to Fig. 3, but with the case in the closed position.

The case comprises two lids or covers A, B, hinged together at one edge in the usual manner and adapted to be held in the closed position by a suitable catch C provided at the opposite edge. The lids A, B are preferably made with ribs or bezels A', B' extending continuously along the four edges. At the side adjacent to the hinge of the case, these ribs A', B' have extensions or tongues which are curled outward so as to form eyes A'', B'', shown best in Fig. 5.

Between the two lids A, B, I provide a holder preferably composed of a central wall D and side members E, F, said wall and members being connected only at their lower portions in any suitable manner, for instance by rivets G. The side members are preferably corrugated so as to form seats or pockets for the individual cigarettes, and are also preferably slightly elastic with a tendency to spring inward so as to firmly hold the cigarettes. The lower portions of the side members are formed with extensions E', F', bent outwardly in opposite directions, then downwardly and slightly inwardly so as to form a shoe adapted to embrace the ribs A', B' adjacent to the hinge. On each extension or shoe portion E', F',

an eye E'', F'' is formed by bending out a narrow strip or tongue and curling this strip to the shape desired. The holder is connected with the case in the following manner: A flexible wire H extending lengthwise of the hinge, is slipped through each of the eyes E'', F'' of the holder, and the ends of these wires are inserted into the eyes A'', B'' of the respective ribs or bezels A', B'. The holder is thus securely fastened to the case.

It will be seen that the wires H assume a different position or shape, according to whether the cigarette-case is open or closed; in the latter case, they are nearly straight, as shown in Fig. 6, while in the open position shown in the other figures, their ends have moved apart, (see Fig. 3) while their central portions remain at the same distance from each other.

Any suitable spring may be provided for throwing the case open when the catch C is released. I prefer however to have the wires H perform this function by making them of spring wire of sufficient stiffness and giving them a normal shape corresponding approximately to that which they assume when the case is fully opened. By normal shape I mean the shape which the wires assume when left to themselves and not restrained by any connection, that is to say, the shape which the wires have before being fitted into the case. When the case is open (Figs. 1 and 3), the springs are under a minimum tension, that is to say, they are approximately in the position which they are given before being put in the case; as the case is being closed, the springs are put under a progressively increasing tension by flexing them or rather straightening them out against their elasticity until they finally assume the position of maximum tension when the case is fully closed as in Fig. 6. The springs will throw the case open as soon as the catch C is depressed or released.

Owing to the fact that the spring wires H press with equal force against both sides of the holder, this latter will always be kept in a central position relatively to the lids A, B. The shoe formed by the lower portions E', F' of the holder members E, F embraces the ribs or bezels A', B' adjacent to the hinge, thus limiting the opening movement of the case, as shown in Figs. 1 and 4. The spring wires H also keep the

shoe in contact with the edges of the bezels so as to give the holder a good support on the lids.

My improved construction does away with the necessity of securing the central holder to the hinge of the case. The cost of manufacture is thus reduced considerably for the reason that such a case need not be manufactured so accurately as if the holder were secured to the hinge of the case.

While I have shown in the drawings a holder adapted to contain ten cigarettes in two rows, I do not wish to limit myself to this particular arrangement. In this respect, as in the construction of the case, various modifications may be made without departing from the nature of my invention as set forth in the appended claims. By suitably choosing the dimensions, the case may be adapted to hold articles other than cigarettes.

I claim:

1. A case of the character described comprising a pair of hinged lids provided with transverse ribs or bezels adjacent to the hinge, a holder within said case, and elastic means securing said holder to said ribs and tending to swing the lids apart.

2. A case of the character described comprising a pair of hinged lids provided with transverse ribs or bezels adjacent to the hinge, a holder within said case, and flexible means for securing the holder to said ribs.

3. A case of the character described comprising a pair of hinged lids, a holder within said case, and flexible wires extending lengthwise of the hinge the central portions of said wires engaging the holder, while

their end portions engage the lids to keep the holder in a central position.

4. A case of the character described comprising a pair of hinged lids, a holder within said case, and flexible wires located on opposite sides of the holder, the central portion of each wire engaging the holder and the end portions of one wire engaging one of the lids, while both end portions of the other wire engage the other lid.

5. A case of the character described comprising a pair of hinged lids, a holder within said case, flexible wires connecting said holder with said lids, the central portions of each wire engaging one of the members connected by such wires, and the end portions engaging the other member.

6. A case of the character described comprising a pair of hinged lids provided with transverse ribs or bezels adjacent to the hinge, eyes formed on said ribs, a holder within said case, eyes formed on said holder, and flexible wires extending through the eyes of the ribs and the eyes of the holder.

7. A case of the character described comprising a pair of hinged lids, eyes formed on said lids at a distance from the hinge, a holder within said case, eyes formed on said holder at a distance from the hinge, and flexible wires extending through the eyes of the lids and the eyes of the holder.

In testimony whereof I have signed this specification in the presence of the subscribing witnesses.

LEO POTTER.
